Frank Gadecki

by Oscar Geier

ATTORNEY

UNITED STATES PATENT OFFICE.

FRANK GADECKI, OF MYSTIC, IOWA.

GUN.

1,269,922.

Specification of Letters Patent. Patented June 18, 1918.

Application filed April 11, 1918. Serial No. 227,881.

To all whom it may concern:

Be it known that I, FRANK GADECKI, a citizen of Poland, residing at Mystic, county of Appanoose, and State of Iowa, have invented certain new and useful Improvements in Guns, of which the following is a specification.

This invention relates to improvements in liquid discharging guns and has as its special object the provision of a device attachable to a rifle or the like, adapted to deliver a stream of blinding liquid at a considerable distance.

A further object is to provide such devices in the form of attachments which may be readily applied or removed from the barrels of the rifles and which are operated in an easy and convenient manner.

These and other like objects are attained by the novel construction and combination of parts hereinafter described and shown in the accompanying drawing, forming a material part of this disclosure, and in which:—

Figure 1 is a side elevational view showing a conventional type of gun and indicating the application of the invention.

Fig. 2 is an enlarged longitudinal sectional view taken through the center of a liquid gun made in accordance with the invention.

Fig. 3 is a similar view of the same, the parts being shown in another position.

Fig. 4 is a transverse sectional view, taken on line 4—4 of Fig. 3.

Fig. 5 is another transverse sectional view taken on line 5—5 of Fig. 3, and

Fig. 6 is a fragmentary bottom plan view indicating the method of securing the device to the gun.

An army rifle or other like support, 10, may be used, to which is attached, by clips 11 and 12, a cylindrical casing 14, the clips being formed of spring material, the extending portions of which act as resilient arms 45 partially surrounding and grasping the gun.

To further support the tube 14, there is at the rear of the case 14, an angular bracket 16, secured by screws 17, the other foot 18 of the bracket having a circular opening 19 from which extends a slot 20, the opening 18 being adapted to receive the head 21, of the screw 22, forming in effect a well known form of bayonet joint, the screw 21 being fixed in the supporting element at all times.

A head 23 is formed at one end of the cylinder 14, the same being imperforate and

into which the screws 17 pass, whereby the device is held to its support. The opposite end of the tube 14 has engaged with it a conical head 24, containing a central longitudinal passage 25, while extending rearwardly into the cylindrical casing 14, from the head 24, is a tube 27, in which is fitted a plunger head 28, connected by the rod 29, with a sliding block 30 from which extend 65 projections 31, fitting the bore of the tube 14, and a handle 32 by which the block can be operated.

A coiled tensional spring 33 surrounds the inner cylinder 27, and is attached at one 70 end to a lug 34, while the other end of the spring is engaged at the outer extremity 35, of a rod 36, secured in the block 30 so as to normally draw the plunger toward the point of the device, the handle element 32 extending outward through a slot 38 formed in the tube 14.

In operation, the device having been attached to a support, the handle lever 32 is drawn back, together with the plunger, from 80 the point 25, and upon it being released, due to the pull of the spring 33, forces the liquid contained in the tube 27, outward through the point or nozzle 25 and it will be obvious that a chemical solution may be used such 85 as would at least temporarily, blind a person subjected to the stream.

Having thus described my invention what I claim as new and desire to secure by Letters Patent, is.

1. In a liquid gun, the combination with an outer cylindrical casing and means for securing said casing to a support, of a conical point secured at one end of said casing, a tube formed with said conical point extending rearward into the casing, a plunger fitted to said tube, means for manually drawing said plunger outwardly, and a spring coiled about said tube adapted to draw said plunger toward said point.

2. In a liquid gun, the combination with a cylindrical casing, means for connecting said casing to a support, a conical point affixed to one end of said casing, and a rigid head at the other end of said casing, of a tube formed with said conical point extending rearwardly into said casing, a plunger slidable within said tube, a plunger rod extending from said plunger toward the rear end of said casing, a block in which said plunger rod is fixed, means for operating said block, a rod engaged with said block

extending parallel of said plunger rod; and beyond said tube, and a spring encircling said tube, one end of said spring being engaged with the inner end of said tube, and 5 its other end engaged with the outer end of said rod whereby said plunger is normally held in a forward position.

3. In a liquid gun, the combination with an outer cylindrical casing, a coned head 10 secured at one end thereof, a tube engaged with said coned head; said tube extending rearwardly into said casing, a plunger movable in said tube, a sliding block in said cylinder, a plunger rod connecting between said

plunger and said block, a handle formed 15 with said block extending outwardly through a slot formed in said cylinder, a rod secured in said block extending parallel to said plunger rod exteriorly of said tube, and a coiled tensional spring surrounding said tube, one 20 end of said spring being engaged at the inner extremity of said tube and the opposite end to the outer extremity of said plunger rod, whereby said plunger and block are held in a normally extended position. 25

In testimony whereof I have affixed my signature.

FRANK GADECKI.
